UNITED STATES PATENT OFFICE.

NOAH CRIM, OF GALTON, ILLINOIS.

HORSE-DETACHER.

SPECIFICATION forming part of Letters Patent No. 378,193, dated February 21, 1888.

Application filed December 12, 1887. Serial No. 257,630. (No model.)

To all whom it may concern:

Be it known that I, NOAH CRIM, of Galton, in the county of Douglas and State of Illinois, have invented a new and Improved Horse-Detacher, of which the following is a full, clear, and exact description.

The object of the present invention is to improve the construction of contrivances applied on and in relation to whiffletrees for the convenient attachment and the instantaneous detachment of the traces therefrom, whereby increased durability and efficiency are secured; and the invention consists in the formation, combination, and arrangement of the parts, all substantially as will hereinafter more fully appear, and be specifically pointed out in the claims.

Reference is to be had to the accompanying drawings, forming a part of this specification, in which similar letters of reference indicate corresponding parts in all the figures.

Figure 1 is a perspective view of one end of a whiffletree with the ferrule of the present invention applied thereto. Fig. 2 is a central longitudinal section thereof. Fig. 3 is a view at right angles to Fig. 2, parts being broken away. Fig. 4 is a view of the outer end of the ferrule, showing a modified construction of the eye. Fig. 5 is a plan view of a double whiffletree, showing as applied thereon connections for securing a simultaneous detachment of the traces therefrom; and Fig. 6 shows the arrangement of the detaching-connections for a single whiffletree.

Upon each end of the whiffletree A is secured a ferrule, B, the outer end of which is formed into an eye or hook, C, and its inner end is socketed at a. From the socket a extends a contracted passage bored in different diameters, as at b and b', shoulders d and d' being thereby formed, and through the wall of said ferrule is formed a longitudinal slot, f. The inner side of the outer bar of the eye C is socketed, as at h.

Within and through the contracted bore is placed a spindle-bolt, D, having an enlarged socketed portion, k, forming a shoulder or step, k', resting on the ferrule-shoulder d'. The bolt is provided with a radial rigidly-attached pin, l, having an eye, l', formed at its outer end, which pin extends outward through the

slot f. A spiral spring, m, bearing by one end in the socket k, is held at its other end by a disk or plate, n, entered in the ferrule-socket and resting upon the shoulder d, where it is 55 there confined by screws p, passed through the ferrule-walls into or against said disk. By means of this spring the bolt D is held extended across the eye C, its end resting in the socket h.

Force applied longitudinally of the whiffletree upon the pin l will carry the projecting end of the bolt-spindle from its bearing in the eye-socket h inwardly across said eye to permit of the engagement or removal of the trace. 65 To facilitate the attachment of the trace, a spring pin or catch, 1, is fitted in the ferrule, so that when the bolt is drawn inward the inner end of said catch will engage a recess, 2, in the socketed portion of the bolt. When the 70 trace is in place in the ferrule-eye, by raising the pin the bolt will be free to engage the trace.

In Fig. 1 the outer end bar, 3, of the eye C is shown as hinged at 4 and engaged at its lower 75 end by a spring-catch, 5. The trace-eye can be placed on the bolt D or removed therefrom by loosening the free end of the bar 3 and swinging the bar outward, as shown by dotted lines in Fig. 1. If preferred, the eye C may 80 be formed solid, as shown in Fig. 4.

In order that all the traces may be simultaneously released, to the eyes l' of the bolt-pins at each end of the whiffletree are secured flexible connections which are guided to a common point, where they may be drawn upon. In Fig. 6 is shown an arrangement of the connections adapted to a single whiffletree, in which cords q q are guided by suitable eyes to the center of the whiffletree, from whence they 90 can be extended upward to the vehicle.

The present invention being especially applicable and useful in connection with double whiffletrees, in Fig. 5 is illustrated an arrangement for securing at one time the operation of 95 all of the detaching devices, and it consists in cords or other suitable connections, q q, secured to and extending from each bolt-pin l of the two whiffletrees to the ends of levers r, centrally pivoted on the main or evener bar A', 100 and from one end of said levers r suitable connections, t, extend to any common point of the

vehicle, by drawing upon which all the bolt-spindles will be withdrawn at the same time and the traces released.

Having thus fully described my invention, I 5 claim as new and desire to secure by Letters Patent—

1. The combination, with a ferrule having the eye C, contracted and shouldered passage b b², and slot f, of the bolt-spindle D, having 10 pin l, and the spiral spring m, substantially as and for the purpose described.

2. The combination, with the ferrule having eye C, passage b b², and slot f, of the bolt-spindle D, having pin l, the spring m, and the 15 spring-catch 1, substantially as and for the purpose stated.

3. The combination, with the ferrule having socketed eye C, socket a, contracted and shouldered passage b b², and slot f, of the shouldered 20 and socketed bolt-spindle D, having pin l, the spiral spring m, and an abutment at the rear of said spring, substantially as and for the purpose described.

4. The combination, with the ferrule B, having 25 eyes C, provided with the hinged bar 3 and means for securing the bar, and slotted at f, of the spring-actuated bolt-spindle D, provided with the pin l, substantially as and for the purpose described.

30 5. The combination, with a whiffletree, of

the ferrules B, having socketed eye C, socket a, contracted and shouldered passage b b², and slot f, the shouldered and socketed bolt-spindles D, having pin l, provided with eye l², the spiral springs m, and the disks n, secured in the 35 ferrule-socket a, all substantially as and for the purpose described.

6. The combination, with the evener bar A² and whiffletrees A A, each provided at their ends with slotted ferrules B, having spring- 40 actuated spindle-bolt provided with pin l, of the pivoted levers r r on said bar A², the connections q between said pins l and the ends of said levers r, and the connections t, all substantially as and for the purpose described.

7. The combination, with a double whiffle-tree comprising the evener-bar A² and the whiffletrees A A, of the ferrules B, having eye C, socket a, contracted passage b b², and slot f, the bolt-spindles D, having pin l, spring m, and abutment therefor, the pivoted levers r on said bar A², the connections q between said pins l and the ends of said levers r, and the connections t, all substantially as shown, and for the purpose described.

NOAH CRIM.
